US0D1034549S

(12) **United States Design Patent** (10) Patent No.: **US D1,034,549 S**
(45) Date of Patent: ** Jul. 9, 2024

(54) **MICROPHONE**

(71) Applicant: **SHENZHEN XUNWEIJIA TECHNOLOGY DEVELOPMENT CO., LTD.**, Shenzhen (CN)

(72) Inventor: **Qibin Mai**, Shenzhen (CN)

(73) Assignee: **SHENZHEN XUNWEIJIA TECHNOLOGY DEVELOPMENT CO., LTD.**, Shenzhen (CN)

(**) Term: **15 Years**

(21) Appl. No.: **29/863,452**

(22) Filed: **Dec. 19, 2022**

(51) LOC (14) Cl. **14-01**

(52) U.S. Cl.

USPC **D14/225**; D14/229

(58) **Field of Classification Search**

USPC D14/228, 225, 227, 229, 226; 381/361; 248/278.1

CPC H04R 1/02; H04R 19/04; H04R 11/04; H04R 1/08; H04B 1/3822; F16M 11/00

(57) **CLAIM**

The ornamental design for a microphone, as shown and described.

DESCRIPTION

FIG. 1 is a front, right and top perspective view of a microphone, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the microphone that form no part of the claimed design.
